UNITED STATES PATENT OFFICE

SAMUEL E. BOUCHARD, OF ROCHESTER, NEW YORK, ASSIGNOR TO BAUSCH & LOMB
OPTICAL COMPANY, OF ROCHESTER, NEW YORK, A CORPORATION OF NEW YORK

DESIGN FOR A SPECTACLE FRAME

Application filed April 28, 1930. Serial No. 35,415. Term of patent 14 years.

To all whom it may concern:

Be it known that I, SAMUEL E. BOUCHARD, a citizen of the United States, and a resident of Rochester, county of Monroe, and State of New York, have invented a new, original, and ornamental Design for Spectacle Frame, of which the following is a specification, reference being had to the accompanying drawing, forming a part hereof.

Fig. 1 is a front elevation of a spectacle frame showing my new design.

Fig. 2 is a top plan view of same.

I claim:

The ornamental design for a spectacle frame substantially as shown.

SAMUEL E. BOUCHARD.
